UNITED STATES PATENT OFFICE.

HENRY A. GOEKEN, OF BUFFALO, NEW YORK, ASSIGNOR TO THE STAR RING COMPANY,
OF BUFFALO, NEW YORK.

RING MOUNTING.

Application filed June 8, 1926. Serial No. 114,503.

This invention relates to a mounting, setting or bezel for finger rings, more particularly to rings of the signet type, but it is to be understood that the mounting can be employed in connection with any type of finger ring for which it is found applicable, and the invention has for its object to provide, in a manner as hereinafter set forth, means whereby an ornament, set or plate provided with an initial, symbol or other design can be quickly and conveniently removed and replaced by a different design of signet, setting or other symbol when desired.

The particular feature of the invention resides in the overcoming of setting up the ring with a permanent setting, but with a mounting for detachably securing the signet, setting or symbol therein, thus ready engraved initialed plates or other ornaments may be carried in stock separately, and the selected plate, ornament or design detachably secured to the ring body and by this arrangement a dealer can always provide the right size of a ring with the desired 25 design, symbol, signet or ornament.

Further objects of the invention are to provide in a manner as hereinafter set forth, a mounting for the purpose referred to, which is simple in its construction and arrangement, strong, durable, including means for conveniently and expeditiously securing or removing a signet or set to or from the ring body and comparatively inexpensive to manufacture.

With the foregoing and other objects in view, the invention consists of the novel construction, combination and arrangement of parts as hereinafter more specifically described and illustrated in the accompanying drawings, wherein is shown an embodiment of the invention, but it is to be understood that changes, variations and modifications can be resorted to which fall within the scope of the claims hereunto appended.

In the drawings wherein like reference characters denote corresponding parts throughout the several views:

Figure 1 is a vertical sectional view of a ring constructed in accordance with this invention and further illustrating the set or signet plate connected within the mounting or bezel therefor.

Figure 2 is an inverted plan view, in section, of the ring.

Figure 3 is an inverted plan view of the

signet plate, the initial being shown in dotted lines.

Figure 4 is a side elevation of the ring with the signet plate secured in position.

In describing the invention in detail the 60 mounting, bezel or setting will be herein-after termed a mounting, and the ornament, jewel, set, or plate provided with an initial, symbol or other design and which is to be secured in the mounting will be herein-after 65 referred to as a set.

Referring to Figures 1 to 4 of the drawings 1 indicates the ring body which is formed with a pair of enlargements 2 terminating in a rectangular portion 3 which 70 forms the mounting for the reception of the set 4.

The enlargements 2 gradually increase in width towards the rectangular portion 3, and the latter is disposed transversely with 75 respect to the ring body. It is to be understood that the enlarged or rather rectangular portion 3 can be of other contour than that as shown, but preferably is as illustrated. The rectangular portion 3 is set up with beveled 80 sides and ends as indicated at 5, 6 respectively. The beveled sides and ends of the rectangular portion 3 are suitably ornamented.

The rectangular portion 3 is formed with 85 a polygonal-shaped opening 7 and the material surrounding the opening 7 is rabbeted to form a vertically disposed shoulder 8 and a seat 9. It is to be understood however that the rabbet conforms in contour to the 90 shape of the set 4 and the latter abuts against the shoulder 8 and is mounted on the seat 9. As shown in Figure 1 the set 4 extends above the shoulder 8.

Positioned transversely with respect to 95 the opening 7, as well as formed integral with the side wall thereof is a supporting bar 10 formed with an intermediate portion 11 and a pair of upstanding and outwardly inclined end portions 12, which are oppositely disposed with respect to each other and merge into the side walls of the opening 7. By setting up the end portions 12 in the manner as stated, the intermediate portion 11 of the bar 10 is inset or disposed below the opening 7. The intermediate portion 11 of the bar 10 is provided with a centrally disposed circular opening 13.

Arranged below the intermediate portion 11 of the bar 10, as well as being pivotally 110

connected to the latter, as at 14 is a triangular shaped locking member 15. The apex of the member 15 is mounted on the pivot 14 and the latter is positioned at one end of the 5 intermediate portion 11 of the bar 10. The member 15, at the larger end or base thereof, is provided with a transversely extending slot formed with a pair of circular end portions 16 and 17 and an intermediate portion 10 18 which connects the end portions together as well as spacing one end portion from the other. The intermediate portion 18 has oppositely disposed arcuate walls 19. The width of the portion 18, at any transverse 15 point thereof is materially less than the diameter of either of the end portions. The length of the intermediate portion 18 is less than the diameter of either of the end portions. The diameter of each of the end portions 20 is substantially equal to the diameter of the opening 13.

As illustrated the set 4 comprises a plate 20 corresponding in contour to the shape of the opening 7 and having its outer face provided with an initial 21. Depending from the lower face of the plate 20 as well as positioned centrally of said face, is a cylindrical shank 22 provided intermediate its ends with an annular groove 23. The lower wall of 25 the groove 23 is positioned nearer the inner end of the shank 22 than the position of the upper wall of the groove 23 with respect to the lower face of the plate 20. The diameter of the shank 22 with respect to the 30 diameter of the opening 13, or with respect to the diameter of the opening 16 or opening 17 is such that said shank can pass through either of the openings referred to. The size of the plate 20 is such that it will 35 snugly fit against the shoulder 8 which is co-extensive with the side and end edges of the plate 20.

When the setting 4 is secured in the mounting, the locking member 15 is shifted 40 so that an opening 16 or an opening 17 will register with the opening 13. The setting 4 is positioned on the seat 9 and the shank 22 extended through the pair of registering 45 openings. The length of the shank 22 is such that it will depend below the locking member 15. After the shank 22 has been 50 extended through the registering openings, the locking member 15 is shifted on its pivot until the walls 19 of the passage 18 are 55 mounted in the groove 23 whereby the walls of the groove will overlap the locking mem-

ber 15 and this arrangement will detachably secure the set 4 in the mounting. To remove the set 4, the locking member 15 is shifted until one of its openings register with the opening 13 and when the locking member is shifted in such position, the walls of the groove 23 are moved from overlapping position with respect to the locking member 15 and under such conditions the set 4 can be removed from the mounting.

It is to be understood that the term "set" applies to any form of design or removable member provided with a shank which is to be secured in the mounting, and further if desired an ornament can be positioned within the mounting, the ornament having a central opening for the passage of the shank of the set, so that the set can be positioned upon the top of the ornament, and with the shank of the set and locking member coacting to detachably secure the ornament and set in position.

It is thought the many advantages of a mounting, in accordance with this invention for the purpose referred to can be readily understood, and although the preferred embodiments of the invention are as illustrated and described, yet it is to be understood that changes in the details of construction can be had which will fall within the scope of the invention as claimed.

What I claim is:

In a finger ring including a removable set having a peripherally grooved shank, the combination of a mounting provided with a set receiving opening, an apertured bar for the passage of the shank extending transversely with respect to said opening and having its ends integral with opposed wall portions of said opening, a shiftable locking member for the passage of the shank pivoted at one end to said bar in proximity to one end of the latter and provided with a slot having a pair of end portions connected together by an intermediate portion and with the end portions of greater area than the intermediate portion, said end portions for selective registration with the aperture in said bar, and the opposed walls of said intermediate portion extending into the grooved shank when one of said end portions is moved out of registration with the aperture in the bar to lock the setting in the mounting.

In testimony whereof, I affix my signature hereto.

HENRY A. GOEKEN,
